UNITED STATES PATENT OFFICE

2,456,748

SPEED GOVERNOR

Ira J. Snader, Detroit, Mich., assignor to Avco Manufacturing Corporation, a corporation of Delaware

Application August 25, 1944, Serial No. 551,152

12 Claims. (Cl. 264—11)

1

The present invention relates generally to speed controlling governors. Although possessing many capabilities of use it is designed or adapted for use in connection with an airplane having a controllable pitch propeller and a propeller driving engine, and operates by varying the pitch of the propeller blades to control or govern the engine so that it operates at a predetermined speed.

One object of the invention is to provide a governor of this type which is an improvement upon, and is more efficient than, previously designed governors of the same general character, including that which is disclosed in, and forms the subject matter of, an application for United States Letters Patent filed by me on December 17, 1943, and serially numbered 514,729, and is characterized by the fact that the operating parts thereof are so arranged, designed and constructed that the governor, when in use or operation, is not so sensitive as to respond to momentary changes in the speed of the engine, such, for example, as those that occur when the engine misfires.

Another object of the invention is to provide a governor of the type under consideration which includes novel and simple means for so controlling the engine that the latter in connection with abrupt or pronounced acceleration or deceleration is quickly brought back to its predetermined speed without hunting.

A further object of the invention is to provide a governor which effectively and efficiently fulfills its intended purpose and is characterized by the fact that it is in the form of a small or compact self-contained unit and may be manufactured at a low or reasonable cost.

Other objects of the invention and the various advantages and characteristics of the present governor will be apparent from a consideration of the following detailed description.

The invention consists in the several novel features which are hereinafter set forth and are more particularly defined by claims at the conclusion hereof.

In the drawings which accompany and form a part of this specification or disclosure and in which like numerals of reference denote corresponding parts throughout the several views:

Figure 1 is a vertical longitudinal section of a governor embodying the invention;

Figure 2 is an end view of the governor;

Figure 3 is a plan view;

Figures 4, 5 and 6 are transverse sections taken respectively on the lines 4—4, 5—5 and 6—6 of Figure 1; and

Figure 7 is a circuit diagram showing the switches which are governor actuated and serve to control the actuating devices of the controllable pitch propeller with which the governor is associated.

2

The governor which is shown in the drawings constitutes the preferred form or embodiment of the invention. It is primarily designed or adapted for use in connection with an airplane (not shown) having a controllable pitch propeller and a propeller driving internal combustion engine (both not shown) and, as hereinafter described, operates by varying the angle of the propeller blades to control or govern the engine so that it runs at a predetermined speed. As its primary or principal parts the governor comprises an elongated housing 15, an engine driven shaft 16, a tubular shaft 17, a shaft 18, an electric pilot motor 19, an inertia member 20 and an actuating element 21.

The housing 15 is preferably formed of cast metal and embodies a horizontally disposed, substantially cylindrical side wall 22 and an end wall 23 at one end of the side wall. The other end of the side wall is provided with an annular series of equidistantly spaced, outwardly projecting, integral lugs 24. The end wall 23 of the housing is preferably formed integrally with the adjacent end of the side wall 22 and defines with said side wall a chamber 25 in which substantially all of the operating parts of the governor are mounted. The upper central portion of the side wall 22 has a circular hole 26 extending transversely therethrough and is provided with an integral, upwardly extending, substantially circular wall 27. The latter is of materially greater diameter than the hole 26 and is positioned in concentric relation with the hole. It has a flat upper end surface and defines a compartment 28 which is closed at the upper end thereof by a cover plate 29. The cover plate 27 fits against the flat upper end of the wall 27 and is removably secured in place by a plurality of vertically extending stud bolts 30. The lower ends of the stud bolts fit within internally threaded sleeve-like lugs 31 on the outer periphery of the wall 27. The upper ends of the bolts extend through holes (not shown) in the cover plate 29 and carry clamp nuts 32. Such nuts, when tightened, serve to clamp the cover plate 29 in place. The portions of the upper ends of the stud bolts that are above the clamp nuts serve as means for maintaining the governor as a whole in its desired operative position with respect to the internal combustion engine that it is designed or adapted to control. The central portion of the cover plate 29 is provided with an integral upwardly extending tubular part 33, the lower end of which communicates with the compartment 28.

The shaft 16 extends transversely of the housing 15 and is journaled in, and extends through, a bearing 34 in the upwardly extending tubular part 33 on the central portion of the removable cover plate 29. The outer end of the shaft 16

is adapted to be connected by a flexible shaft or other coupling (not shown) to one of the driven elements or parts of the engine, such, for example, as the cam shaft, in order that the shaft 16 is driven conjointly with the engine. The inner end of the shaft 16 projects into the compartment 28.

The tubular shaft 17 extends longitudinally of, and is disposed centrally within, the housing 15 and surrounds and is journaled on the shaft 18. It is held against axial displacement, as hereinafter described, and is driven by the engine driven shaft 16 through the medium of a hydraulic clutch 35, a pair of bevel gears 36 and 37 and planetary gearing 38. The hydraulic clutch 35 is disposed in the compartment 28 and comprises a casing 39 and a driven or out-put shaft 40 as well as operating parts within the casting. The inner or lower end of the engine driven shaft 16 projects into the upper portion of the casing 39 and serves to drive the operating parts within the casing. The out-put shaft 40 projects downwards from the lower portion of the casing 39 and is in axial alignment with the engine driven shaft 16. The hydraulic clutch 35 is of the type or variety that permits free drive or rotation of the engine driven shaft 16 while the operating parts of the governor are at rest. When, however, the governor is operated as hereinafter described, by starting the pilot motor 19, drive of the clutch out-put shaft 40 takes place and such shaft is driven at the same speed as the engine driven shaft 16 within predetermined torque limits. When the torque exceeds a predetermined value the oil or other fluid in the housing shears and prevents the abnormally high torque from being transmitted to the out-put shaft 40 with the result that drive of the shaft 40 by the engine driven shaft 16 ceases. The clutch 35 is of standard or conventional construction and is so designed that when the governor is in operation while the shaft 16 is being driven from the engine the out-put shaft 40 is driven conjointly with the shaft 16. As shown in Figure 1, the out-put shaft 40 projects into the upper central portion of the chamber 25 in the housing 15 and is rotatably supported by way of a ball bearing 41. The latter comprises an outer race 41^a, an inner race 41^b and an annular series of balls 41^c between the two races. The outer race is connected by a drive fit to the portion of the housing side wall 22 that defines the hole 26. The inner race 41^b of the ball bearing 41 is keyed or otherwise fixedly secured to the central portion of the clutch out-put shaft 40. The bevel gear 36 is mounted on the lower end of the out-put shaft 40 and is held in fixed relation with the out-put shaft as the result of being clamped against the inner race 41^b of the ball bearing 41 by a nut 42. It meshes with, and normally serves to drive, the bevel gear 37 which, as shown in Figure 1, surrounds the central portion of the tubular shaft 17 and embodies a body 37^a and a hub 37^b. The hub is journaled on, or rotatably mounted about, an enlarged, integral, bearing-forming part 43 on the central portion of the tubular shaft 17. The body 37^a of the bevel gear 37 together with the hub 37^b forms the spider for the planetary gearing 38. The latter comprises a ring gear 38^a, a pair of planetary pinions 38^b and a sun gear 38^c. The ring gear 38^a is secured within the inner periphery of the housing side wall 22 by a drive fit and abuts against an annular shoulder 44. The planetary pinions 75

38^b are in mesh with the ring gear 38^a and are positioned one diametrically opposite the other. They are mounted on a pair of stub shafts 45 and these are connected to diametrically opposite portions of the body 37^a of the bevel gear 37. The sun gear 38^c is disposed between and meshes with the planetary pinions 38^b and is preferably formed integrally with the tubular shaft 17. Preferably the planetary gearing 38 is located on the side of the bevel gear 37 that faces the open or lug equipped end of the housing side wall 22. When the governor is in operation the tubular shaft 17 is driven from the engine driven shaft 16 through the medium of the hydraulic clutch 35, the bevel gears 36 and 37 and the planetary gearing 38. For purposes of the present disclosure it will be assumed that the engine driven shaft 16 is driven in a counterclockwise direction as viewed in Figure 3. Because of the arrangement of the various gears and pinions the tubular shaft 17, when viewed from the end of the housing 15 having the end wall 23, will be driven in a clockwise direction.

The shaft 18 extends longitudinally of, and is centrally disposed in, the governor housing 15 and, as hereinbefore pointed out, serves as a journal for the tubular shaft 17 which is driven by the engine driven shaft 16. The end of the shaft 18 that is disposed adjacent the end wall 23 of the housing is provided with a reduced stem 18^a and this is journaled in a bearing 46 on the central inner portion of the housing end wall 23. The other end of the shaft 18, i. e., the end that is disposed adjacent the lug equipped end of the housing side wall, embodies an enlargement 18^b which has at its outer end a pair of radially extending diametrically opposite arms 18^c. A collar 47 on the shaft 18 coats with the inner end of the enlargement 18^b to hold the tubular shaft 17 against axial displacement relatively to the shaft 18.

The electric pilot motor 19 is located adjacent the lug equipped end of the housing side wall 22 and operates through the medium of planetary gearing 48 to drive the shaft 18. It is a direct current motor and comprises a casing 49 and an armature 50. One end of the motor casing is provided with an outwardly extending annular flange 49^a and this fits against the open end of the housing side wall 22 and is connected thereto by way of bolts 51. The latter extend through aligned or registering holes in the flange 49^a and the lugs 24 on the open end of the housing side wall and serve removably to secure the electric pilot motor 19 in place. If desired a synchronous motor may be used instead of the electric pilot motor 19 and the frequency of the alternating current that is supplied thereto may be varied to cause the motor to operate at the desired speed. The armature 50 is rotatably mounted in the casing 49 and is arranged so that the shaft thereof is in axial alignment with the shaft 18. A battery 52 serves to supply current to the pilot motor 19. One side of the battery is connected to one of the terminals of the motor by way of a conductor 53 and the other side of the battery is connected to the other motor terminal by way of a conductor 54. The last mentioned conductor is provided with a switch 55 and a rheostat 56. The rheostat serves as a medium for varying or changing the speed of the electric pilot motor 19 when the switch 55 is closed. It is of conventional or standard construction and comprises a resistance element 56^a and a rotary arm 56^b. The arm is movable over

the resistance element in order that more or less of said element may be cut into or out of the circuit for the pilot motor 19. The armature of the electric pilot motor is driven in the same direction as the tubular engine driven shaft 17, i. e., in a clockwise direction as viewed from the end of the governor housing having the end wall 23. When the pilot motor is in operation the governor, as hereinafter described, operates to control the engine so that it runs at a predetermined speed, i. e., a speed which is directly proportional to the speed of the pilot motor. By controlling the speed of the pilot motor through the medium of the rheostat 56 the predetermined speed of the engine as controlled by the governor may be correspondingly varied.

The planetary gearing 48 serves to drive the shaft 18 from the armature of the electric pilot motor 19 and comprises a sun gear 48^a, a pair of planetary pinions 48^b and a ring gear 48^c. The sun gear 48^a is keyed or otherwise fixedly secured to the inner end of the armature shaft of the armature, as shown in Figure 1. The planetary pinions 48^b mesh with, and are driven by, the sun gear. They are positioned one diametrically opposite the other and are rotatably mounted on stub shafts 51 which extend lengthwise of the governor housing 15 and are mounted on the outer ends of the arms 61. Such arms together with the enlargement 18^b of the shaft 18 constitute the spider of the planetary gearing 48. The ring gear 48^c is fixedly secured within the lug equipped end of the side wall 22 of the governor housing 15 and abuts against an annular shoulder 52. When the pilot motor 19 is in operation it operates through the medium of the planetary gearing 48 to drive the shaft 18 in the same direction as the engine driven tubular shaft 17 which, as heretofore pointed out, is a clockwise direction when the shafts 17 and 18 are viewed from the end of the governor housing with the end wall 23. The planetary gearing 48 is such that when the engine is operated or running at its predetermined speed as determined by the speed of operation of the motor 19 the shaft 18 is driven at the same speed as the tubular engine driven shaft 17.

In addition to the parts heretofore described the governor comprises a connection between the shafts 17 and 18 which limits relative rotation of the two shafts in either direction. Such connection forms a positive drive between the two shafts after one shaft has been rotated relatively to the other to a predetermined extent and consists of a pair of coaxing diametrically opposite rotary members 59. Such members are positioned adjacent the enlargement 18^b on the shaft 18 and are rotatably supported by way of a pair of stub shafts 60. As shown in Figure 1, the stub shafts 60 are arranged in parallel relation with, and on opposite sides of, the shaft enlargement 18^b and are disposed in the housing 15 between the planetary gearing 38 and the planetary gearing 48. The ends of the stub shafts that extend in the direction of the planetary gearing 38 are fixedly connected to the outer ends of a pair of radially extending diametrically opposite arms 61 on the end of the tubular shaft 17 which is adjacent the electric pilot motor 19. Such arms are preferably formed as integral parts of the tubular shaft 17. The other ends of the stub shafts 60, i. e., the ends that project or extend in the direction of the planetary gearing 48, extend through apertures in the central portions of the members 59. Nuts 62 on said

other ends of the stub shafts 60 serve in conjunction with the outer ends of the arms 61 to hold the members 59 against axial displacement with respect to the stub shafts while at the same time they permit the members to rotate freely relatively to the stub shafts. The inner and side portions of the members 59 are provided with arcuate slots 63 through which the inner end of the shaft enlargement 18^b extends. As shown in Figure 1, the inner portions of the members 59 are arranged in lapped or axially offset relation. Preferably the slots 63 extend throughout an arc of approximately 270°. The portions of the members 59 that define the outer side parts of the slots 63 are shaped to define internal teeth 64 and these teeth mesh with an annular series of longitudinally extending teeth 65 on the inner end of the enlargement 18^b on the motor driven shaft 18. The outer portions of the members 59 are provided with large sized enlargements constituting weights 66 and these are positioned midway between the ends of the arcuate slots 63. When the engine with which the governor is associated is operating or running at its predetermined speed and as a result the shafts 17 and 18 revolve at the same speed the weights 66, in response to the action of centrifugal force, maintain the members 59 in a position wherein the tooth equipped inner end of the shaft enlargement 18^b is disposed in the central portions of the arcuate slots 63. Should, however, the engine deviate from its predetermined speed the tubular engine driven shaft 17 either overruns or underruns the shaft 18 and causes the members 59 to revolve about the stub shafts 60. The members 59 will revolve until the tooth equipped inner end of the shaft enlargement 18^b strikes against or is brought into abutment with the trailing ends of the slots 63. When such tooth equipped end abuts against the trailing ends of the slots the two shafts 17 and 18 are connected together for conjoint rotation. When the engine accelerates beyond its predetermined speed the members 59 revolve in a clockwise direction as viewed in Figure 5 until the tooth equipped inner end of the shaft enlargement 18^b strikes against the slot ends 63^a. In the event that the engine decelerates from its predetermined speed the members 59 revolve in a counter-clockwise direction as viewed in Figure 5 until the tooth equipped inner end of the shaft enlargement 18^b strikes against the slot ends 63^b. It is contemplated that the engine with which the governor is associated will be started before the switch 55 of the circuit for the electric pilot motor 19 is closed. In connection with starting of the engine the out-put shaft 40 of the hydraulic clutch 35 and the other parts of the governor remain stationary. As soon as the engine is started and the switch 55 is closed so as to start the motor 19 the shaft 18 is set in motion and operates through the medium of the members 59, the planetary gearing 38, the bevel gear 37 and the bevel gear 36 to revolve the clutch out-put shaft 40. As soon as the shaft 40 is brought up to speed the clutch 35 is energized or rendered operative with the result that the engine driven shaft 16 operates through the medium of the clutch, the bevel gears 36 and 37 and the planetary gearing 38 to drive the tubular shaft 17. As heretofore pointed out, when the engine is driven at its predetermined speed the shafts 17 and 18 are driven at the same speed and revolve together and the weights 66 maintain the members 59 in their normal position wherein

the tooth equipped inner end of the shaft enlargement 38^b is disposed in the central portions of the slots 63. Either gradual or abrupt acceleration or deceleration of the engine from its predetermined speed does, however, result in limited overrunning or underrunning of the shaft 17 with respect to the shaft 18. Because the weights 66 are subjected to centrifugal action and tend to hold the members 59 against rotation they operate to counteract relative rotation of the shafts 17 and 18 when the engine momentarily decelerates in connection with misfiring.

The inertia member 20 of the governor is in the form of a disc and has a central circular aperture 67 through which extends loosely the end of the tubular engine driven shaft 17 that is disposed adjacent the housing end wall 23. It is formed of any suitable substantially heavy material, such as metal, and by reason of the manner in which it is mounted it is slideable axially and rotatably relatively to the shaft 17. As hereafter pointed out more in detail, the member 20 rotates conjointly with the shaft 17 in connection with gradual acceleration and deceleration of the engine but, due to its inertia, underruns the shaft 17 in connection with abrupt acceleration of the engine and, due to its momentum overruns the shaft 17 in connection with abrupt deceleration of the engine. On the side thereof that faces the housing end wall 23 the inertia member 20 is provided with a fixed collar-like element 68. This element surrounds the adjacent end of the tubular engine driven shaft 17 and embodies an external screw thread 69 and an internal screw thread 70. Such screw threads are preferably arranged in the same direction and are right hand screw threads. The internal screw thread 70 is arranged in interfitting or screw thread relation with a right hand male or external screw thread 71 on the tubular engine driven shaft 17. When the inertia member 20 underruns the shaft 17 in connection with abrupt acceleration of the engine the member together with the collar-like element 68 is shifted axially toward the housing end wall 23 in view of the action of the screw threads 70 and 71. When the member 20 overruns the shaft 17 in connection with abrupt or pronounced deceleration of the engine such member together with the element 68 is shifted axially away from the housing end wall 23 in response to the action of the interfitting screw threads 70 and 71.

The inertia member 20 is controlled by a pair of diametrically opposite coacting members 72 so that it rotates conjointly with the tubular engine driven shaft 17 except when such shaft abruptly or pronouncedly accelerates or decelerates in response to abrupt acceleration or deceleration of the engine with respect to its predetermined speed. The members 72 are constructed like, and in a measure operate in the same manner as, the members 59. They are in the form of discs, have central apertures 73 and are positioned on opposite sides of the shaft 17 and adjacent the side of the inertia member 20 that faces in the direction of the electric pilot motor 19. Pivot bolts 74 extend through the apertures 73 and serve to support the members 72 so that they are rotatable about their centers. Such bolts are arranged in parallel relation with the tubular shaft 17 and also extend through holes 75 in the inertia member 20. The inner ends of the pivot bolts fit within screw threaded sockets 76 in the collar-like element 68 with the result that such element is retained in fixed or rigid relation with the

inertia member. The inner and side portions of the members 72 are provided with arcuate slots 77 through which extends the adjacent end of the tubular engine driven shaft 17. As shown in Figure 6, the slots 77 extend through approximately 270° arcs. The portions of the members 72 that define the outer peripheral parts of the slots 77 are shaped to form internal teeth 78 which mesh with an annular series of longitudinally extending teeth 79 on the adjacent end of the shaft 17. The members 72 are arranged in lapped or longitudinally offset relation and have at the outer portions thereof integral enlargements constituting weights 80. Such weights, in response to the action of centrifugal force, cause the members 72 to assume a position wherein the teeth 79 are disposed in the central portions of the slots 77 when the engine is operating at its predetermined speed or gradually accelerates or decelerates with respect to its predetermined speed. When the engine abruptly accelerates the inertia member 20, due to its inertia, underruns the tubular shaft as hereinbefore pointed out and the members 72 revolve in one direction about the pivot bolts 74 until certain ends of the slots 77 are brought into abutment with the teeth 79 at which time the member 20 is connected for conjoint drive with the shaft 17. When the engine with which the governor is associated abruptly or pronouncedly decelerates the inertia member 20, due to its momentum, overruns the shaft 17 and the members 72 revolve in the opposite direction until the other ends of the slots 77 are brought into abutment with the teeth 79 at which time the member 20 is again connected for conjoint drive with the shaft 17. Generally speaking, the members 72 cause the inertia member to rotate conjointly with the shaft 17 when the engine is operating at its predetermined speed or gradually accelerates or decelerates with respect to such speed and permit the member to underrun the shaft 17 to a limited extent in connection with abrupt acceleration of the engine and to overrun the shaft 17 in connection with abrupt deceleration of the engine. As previously pointed out, the inertia member 20 is axially displaced by the screw threads 70 and 71 away from the pilot motor 19 when it underruns the shaft 17 in connection with abrupt acceleration of the engine and said member is shifted by such threads away from the housing end wall 23 when it overruns the shaft 17 in connection with abrupt deceleration of the engine.

The actuating element 21 is composite in character and comprises a collar 81, a pair of rods 82 and a bar 83. The collar is disposed between the element 68 and the housing end wall 23 and surrounds the adjacent end of the motor driven shaft 18. It is connected to such end of the shaft 18 by splines 84 in order that it is driven conjointly with the shaft while at the same time it is permitted to slide axially relatively thereto. The inner end of the collar 81, i. e., the end that faces in the direction of the inertia member 20, is provided with a pair of diametrically opposite arms 85 and these extend outwards, then horizontally and then inwards. The inwardly extending portions of the arms 85 fit within the external screw thread 69, are designated by the reference numeral 85^a, and in effect constitute cam followers. The screw thread 69 is so arranged that when the element 68, together with the inertia member 20, overruns the motor driven shaft 18 to a limited extent, due to gradual acceleration of the engine, the collar 81 is shifted to

a limited extent towards the housing end wall 23, and when the element 68, together with the inertia member 20, underruns the shaft 18 to a limited extent, due to gradual deceleration of the engine, the collar 81 of the actuating element 21 is shifted to a limited extent away from the housing end wall 23. The extent of overrunning and underrunning of the inertia member 20 with respect to the shaft 18 is determined by the slots 63 in the members 59. The screw thread connection consisting of the screw threads 70 and 71, i. e., the screw thread connection between the collar-like element 68 and the tubular engine driven shaft 17 coacts with the screw thread 69 and the arm ends 85^a in such manner that when the inertia member 20 underruns the shaft 18 to a limited extent due to abrupt acceleration of the engine the collar 81 is shifted towards the housing end wall 23 to a greater extent and when the inertia member overruns the shaft 17 to a limited extent due to abrupt deceleration of the engine the collar 81 of the actuating element 21 is shifted axially to a greater extent away from the housing end wall 23. The extent of overrunning and underrunning of the inertia member 20 with respect to the engine driven shaft 17 is determined by the slots 71 in the members 72. The rods 82 of the actuating element 21 are positioned on opposite sides of, and are disposed in parallel relation with, the shafts 17 and 18. The central portions of the rods 82 extend loosely through holes 86 in the outer portion of the housing end wall 23 in order that the rods are slidable longitudinally of the housing 15. The inner ends of the rods are fixedly connected to a ring 87 which surrounds, and is spaced outwards of, the collar 81. The rods 82 are connected to the collar 81 by a ball bearing 88 in order that they slide or shift conjointly with the collar 81. Said ball bearing 88 comprises an outer race 88^a, an inner race 88^b and an annular series of balls 88^c between the two races. The outer race 88^a fits within the inner periphery of, and is secured to, the ring 87 which, as previously pointed out, is fixedly connected to the inner ends of the rods 82. The inner race 88^b of the ball bearing 88 fits around the outer periphery of, and is suitably fixedly secured to, the collar 81. The bar 83 of the actuating element 21 extends between the outer or exteriorly disposed ends of the rods 82 and has its ends fixedly secured to said ends of the rods. As the result of the fact that the bar 83 is fixedly connected to the rods 82 it moves away from and towards the housing end wall 23 in conformity with outward and inward shift of the collar 81.

As previously pointed out, the governor is adapted to control or govern the speed of the airplane engine with which it is associated by varying the angle of the propeller blades of the controllable pitch propeller. The controllable pitch propeller which is disclosed in, and forms the subject matter of, an application for United States patent filed by Archibald G. Forsyth on August 12, 1943, Serial No. 498,367, now abandoned, represents one form or type of controllable pitch propeller with which the present governor is designed for use. Such controllable pitch propeller includes in addition to a hub and axially rotatable blades on the hub, pitch change mechanism including a magnetic clutch type device for effecting increase in the pitch of the propeller blades at a slow rate, a magnetic clutch type device for effecting decrease in the pitch of the propeller blades at a slow rate, a magnetic clutch

type device for effecting increase in pitch of the propeller blades at a fast rate, and a magnetic clutch type device for effecting decrease in pitch of the propeller blades at a fast rate. Such devices are diagrammatically illustrated in Figure 7 of the drawings and are designated, respectively, by the reference numerals 89, 90, 91 and 92. These four devices are controlled, respectively, by normally open push button switches 93, 94, 95 and 96. Such switches are mounted on a bracket structure 97 on the exterior of the housing end wall 23 and, as hereinafter described, are controlled automatically in response to axial shift of the actuating element 21. The switches 93 and 94 are positioned in straddled relation with one end of the bar 83 and are arranged so that the buttons thereof face or oppose one another and are spaced an extremely small distance from said one end of the bar, as shown in Figure 1. The switch 93 is disposed outwards of the bar and the switch 94 is disposed inwards of the bar. The switches 95 and 96 are positioned in straddled relation with the other end of the bar and are located to one side of the switches 93 and 94, respectively. They are arranged so that their buttons face one another and are spaced apart a distance greater than the distance between the buttons for the switches 93 and 94. When the governor is in its neutral or non-governing position the bar 83 of the actuating element 21 is disposed midway between the buttons for the switches 93 and 94 and midway between the buttons for the switches 95 and 96. The switch 95 is positioned outwards of the bar 84 and the switch 96 is positioned inwards of the bar. Closing of the switch 93 results in closing of the hereinafter described circuit for the device 89 and results in the propeller blades being increased in pitch at a slow rate and the engine correspondingly decreasing in speed. When the actuating element 21 is shifted outwards to a limited extent as the result of the cam arrangement in the form of the screw thread 69 and arm ends 85^a being brought into play because of a gradual increase in speed of the engine over the predetermined speed the bar 83 effects closing of the push button switch 93 for the slow rate increase pitch device 89. When the actuating element 21 is shifted to a limited extent in the opposite direction, i. e., inwards, as the result of said cam arrangement being brought into play due to the engine gradually decreasing in speed the bar 83 effects closing of the switch 94 for the slow rate decrease pitch device 90. Closing of such switch 94 completes the hereinafter described circuit for the device 90 and results in the propeller blades being decreased in pitch at a slow rate and a corresponding increase in speed of the engine. When the actuating element 21 is shifted outwards to a greater extent in connection with abrupt increase in speed of the engine the bar 83 effects closing of the switch 95 for the fast rate increase pitch device 91. Closing of the switch 95 completes the circuit for the device 91 and results in the propeller blades being increased in pitch at a fast rate. When the actuating element 21 is shifted inwards to a greater extent in connection with abrupt decrease in speed of the engine the bar 83 effects closing of the switch 96 for the fast rate decrease pitch device 92. Closing of the switch 96 completes the hereinafter described circuit for the device 92 and results in a fast rate decrease in the pitch of the propeller blades. Due to automatic control of the switches by the governor the engine

is governed so that it maintains a predetermined speed corresponding to the speed of drive of the motor driven shaft 18.

The circuit for the slow rate decrease pitch device 90 comprises a battery 93, a conductor 99 leading from one side of the battery to one terminal of the device 90, a conductor 100 leading from the other terminal of the device 90 to one contact of a normally closed switch 101, a conductor 102 leading from the other contact of the switch 101 to one contact of the push button 94, and a conductor 103 leading from the other contact of the switch 94 to the other side of the battery. When the switch 94 is closed, as hereinbefore described, the aforementioned circuit is closed with the result that the device 90 decreases the pitch of the propellers at a slow rate and causes the engine to accelerate or increase in speed. As the engine accelerates to its predetermined speed the actuating element 21 is automatically shifted to its neutral position, thereby resulting in opening of the switch 94.

The circuit for the slow rate increase pitch device 89 includes the battery 93 and comprises a conductor 104 leading from the conductor 99 to one contact of the push button switch 93, a conductor 105 leading from the other contact of the switch 93 to one contact of a normally closed switch 106, a conductor 107 leading from the other contact of the switch 106 to one terminal of the slow rate increase pitch device 89, and a conductor 108 leading from the other terminal of the device 89 to the conductor 103. When the switch 93 is automatically closed as the result of the engine gradually accelerating or over-speeding the aforementioned circuit is completed with the result that the device 89 causes a slow rate increase in pitch of the propeller blades and the engine decreases in speed. As the engine decreases in speed to its predetermined speed the bar 83 is automatically shifted into its normal or neutral position and the switch 93 opens, thus breaking the circuit for the device 89.

The circuit for the fast rate decrease pitch device 92 comprises a conductor 109 leading from the conductor 99 to one terminal of the device 92, a conductor 110 leading from the other terminal of the device 92 to one contact of the switch 96, and a conductor 111 leading from the other contact of the switch 96 to the conductor 103. As shown in Figure 7 the conductor 110 includes a solenoid 112 which is operatively connected to the switch 101 in the circuit for the slow rate decrease pitch device 90 and serves when the circuit for the device 92 is closed as the result of closing of the switch 96, to open the switch 101 and break the circuit for the device 90. When the switch 96 is closed as the result of the engine abruptly under-speeding or decelerating the circuit through the device 92 is completed with the result that the propeller blades are decreased in pitch at a fast rate. As soon as the engine speeds up to the speed determined by the pilot motor 19 the actuating element 21 will have shifted to its neutral position and the switches 94 and 96 thereby opened, and thus effecting an opening of the circuit for the devices 90 and 92. The solenoid 112 for opening the switch 101 is included in the circuit for the fast rate decrease pitch device 92 as hereinbefore described. Pronounced inward shift of the actuating element 21 in connection with initial abrupt deceleration or under-speeding of the engine causes the bar 83 of the element to close the switch 94 before it closes the switch 96. However, as soon as the switch 96 is closed the

circuit for the slow rate decrease pitch device 90 is automatically opened as the result of the action of the solenoid 112 even though the switch 94 is held in its closed position by the bar 83.

The circuit for the fast rate increase pitch device 91 includes the battery 93 and comprises a conductor 113 leading from the conductor 99 to one contact of the switch 95, a conductor 114 leading from the other contact of the switch 95 to one terminal of the device 91, and a conductor 115 leading from the other terminal of the device 91 to the conductor 103. The conductor 114 includes a solenoid 116 which is operatively connected to the normally closed switch 106 in the circuit for the slow rate increase pitch device 89 and serves when the circuit for the device 91 is closed, to open the switch 106 and thus break the circuit for the device 89. When the switch 95 is closed as the result of the engine initially abruptly accelerating or over-speeding the circuit for the device 91 is closed with the result that such device increases the pitch of the propeller blades at a fast rate. When the speed of the engine is decreased to the predetermined speed as set by the motor 19 the actuating element 21 will have been automatically shifted to its neutral position, resulting in opening of the switches 93 and 95. The solenoid 116 is included in the circuit for the device 91 because when the bar 83 is moved outwards in connection with initial abrupt acceleration or over-speeding of the engine the switch 93 is closed before the switch 95 and it is hence necessary to break or open the circuit for the device 89 as soon as the circuit for the device 91 is closed by closing of the switch 95. When the switch 95 is closed the solenoid 116 maintains the normally closed switch 106 in its open position and hence the circuit for the slow rate increase pitch device 89 is opened even though the switch 95 is closed.

The operation of the governor is as follows:

As heretofore pointed out it is contemplated that the engine with which the governor is associated will be started before the electric pilot motor 19 is set in operation. During starting of the engine the operating parts of the governor, with the exception of the engine driven shaft 16, remain stationary or at rest due to the action of the hydraulic clutch 35. After the engine is started and is brought to approximately the desired predetermined speed the switch 55 in the circuit for the motor 19 is closed. Closing of the switch results in drive of the armature 59 of the motor and resultantly causes drive of the shaft 18 through the medium of the planetary gearing 48. Drive or rotation of the shaft 18 sets in motion the out-put shaft 40 of the hydraulic clutch in view of the driving connection consisting of the members 59, the shaft 17, the planetary gearing 38 and the bevel gears 37 and 36. As soon as the out-put shaft 40 is set in motion the hydraulic clutch 35 becomes operative with the result that the out-put shaft 40 is connected for conjoint drive by the engine driven shaft 16. As soon as the clutch is operative the shaft 17 is driven from the shaft 16 through the medium of the clutch 35, the bevel gears 36 and 37 and the planetary gearing 38. When the speed of the engine corresponds to the speed predetermined by the electric pilot motor 19 the shaft 17 and 18 rotate at the same speed and the actuating element 21 assumes its neutral or no governing position wherein its bar 83 is disposed midway between the buttons for the switches 93 and 94 and midway between the buttons for the switches 95 and 96. So long as the speed of the engine corresponds to the

speed that is determined by the pilot motor the actuating element remains in its neutral position and the four switches 93, 94, 95 and 96 are open. In the event that the engine gradually increases in speed for any reason whatsoever the shaft 17 and the collar-like element 68 slowly overrun the shaft 18. The element 68 overruns the shaft 18 because, as heretofore pointed out, it is connected to the inertia member 20 and the latter, due to the action of the members 72, rotates conjointly with the shaft 17 in connection with gradual acceleration of the engine. When the element 68 overruns the shaft 18 in connection with gradual acceleration of the engine the actuating element 21 is shifted outwards to a limited extent by the action of the external screw thread 69 and the arm ends 85^a and results in the bar 83 closing the switch 93 and resultant actuation of the slow rate pitch device 89. Immediately upon actuation of such device the propeller blades are increased in pitch at a slow rate with the result that the engine slows down or decelerates. As the engine slows down or decelerates to its predetermined speed the members 59, due to the centrifugal action of the weights 66, rotate back to their normal position wherein the tooth equipped inner end of the enlargement 18^b is disposed in the central portions of the slots 63, and resultantly cause the shaft 17 reversely to rotate with respect to the motor driven shaft 18. Such reverse relative rotation on the part of the shaft 17 operates through the medium of the external screw thread 69 on the element 68, to shift the actuating element 21 back to its neutral or no governing position. As soon as the actuating element returns to its normal position the switch 93 opens and stops actuation of the slow rate increase pitch device 89. It is contemplated that the actuating element will be shifted to its normal position at the time the engine slows down or decelerates to its predetermined speed.

In the event that the engine gradually decreases in speed for any reason whatsoever the shaft 17 together with the inertia member 20 and the collar-like element 68 underruns the motor driven shaft 18, and the external screw thread 69 and the arm ends 85^b coact to shift the actuating element 21 inwards to a limited extent and thus effect closing of the switch 94 for the slow rate decrease pitch device 90. Immediately upon actuation of such device 90 as the result of closing of its switch 94 the propeller blades are decreased in pitch at a slow rate with the result that the engine increases in speed until it reaches its predetermined or governed speed. As the engine approaches its predetermined speed the members 59, in response to the action of the weights 66, rotate back to their normal position and cause such reverse rotation of the shaft 17, inertia member 20 and the element 68 relatively to the motor driven shaft 18 as to result in the screw thread 69 and the arm ends 85^a shifting the actuating element 21 back to its normal position. As soon as the element 21 is shifted back to its normal position the switch 94 opens and effects stoppage of the slow rate decrease pitch device 90. It is contemplated that the device 90 will cease operation immediately upon the engine returning to its predetermined speed.

In the event that the engine should abruptly accelerate as the result of the airplane being placed in a steep or sharp dive the operation of the governor is as follows:

At the initial part of abrupt acceleration of the engine the inertia member 20 and the collar-

shaped element 68, due to inertia, underrun to a limited extent the engine driven shaft 17 and cause rotation of the members 72 and their pivot bolts 74. Due to underrunning of the element 68 with respect to the engine driven shaft the internal screw thread 70 coacts with the screw thread 71 on the shaft 17 to shift the inertia member and the element 68 outwards to such an extent as to cause closing of the switch 93 for the slow rate increased pitch device 89. As soon as the inertia member underruns the engine driven shaft 17 to the extent permitted by the slots 77 in the members 72 the member is connected for conjoint drive with the shaft 17 and due to the fact that the shaft 17 is overrunning the shaft 18 the cam arrangement in the form of the screw thread 69 and the arm ends 85^a shifts the actuating element 21 outwards such an additional distance as to effect closing of the switch 95 for the fast rate increase pitch device 91. As soon as the switch 95 closes the fast rate increase pitch device 91 is set in operation and increases the pitch of the propeller blades at a fast rate. The switch 95 remains closed so long as there is an increase in the rate of acceleration of the engine. As soon as there is no increase in the rate of acceleration of the engine as the result of increase in pitch of the blades at a fast rate the inertia member 20 and the collar-shaped element 68 return to their normal or neutral position as a result of the action of the coacting rotary members 72. Return of the inertia member to its neutral position brings into play the cam arrangement in the form of the screw threads 70 and 71 and results in the actuating element 21 being shifted back to such an extent as to effect opening of the switch 95. Such limited shiftback of the actuating element is not, however, sufficient to effect opening of the switch 93 for the slow rate increase pitch device 89. So long as the last mentioned switch is closed the slow rate increase pitch device 89 is effective to increase the pitch of the propeller blades at a slow rate. After the engine reaches its peak of acceleration it starts abruptly to decelerate. During deceleration of the engine before the engine reaches its pre-determined speed, as set or determined by the electric pilot motor 19, the inertia member 20 and the collar-shaped element 68 due to their momentum overrun the engine driven shaft 17 and cause the cam arrangement in the form of the screw threads 70 and 71 to shift the actuating element 21 inwards to its neutral position even though the cam arrangement in the form of the screw thread 69 and the arm ends 85^a are effective. After return of the element to its neutral position the engine, due to the momentum of its parts, slows down to its predetermined speed. The point at which the actuating element is returned to its neutral position prior to levelling off of the engine to its predetermined speed depends upon the degree of abruptness of deceleration. If the magnitude or degree of abruptness of deceleration is great then the actuating element 21 will be shifted to its no governing position in connection with deceleration of the engine quite a bit ahead of the engine decelerating to its predetermined speed. If the degree of abruptness of deceleration is comparatively small then the actuating element 21 will be returned to its neutral position at a point directly in advance of the engine due to its momentum levelling off to its predetermined speed, i. e., the speed determined or fixed by the pilot motor 19. In view of the manner in which the 75 rotary members 72 coact with the governor as

sumes a no governing position in advance of the engine reaching the predetermined speed after abrupt acceleration and hence the engine will automatically level off to its predetermined speed with substantially no hunting. In other words, the arrangement of the governor is such that in connection with pronounced or abrupt acceleration of the engine for any reason whatsoever the switches for the fast and slow rate increase pitch devices are opened ahead of the time when the engine levels off to its predetermined speed, thus compensating for the momentum effect of the engine which would normally cause the engine to pass its predetermined speed and result in hunting under governor control. The compensating or anticipating feature of the present governor in connection with abrupt acceleration is entirely automatic and self-adjusting, depending upon the magnitude of abrupt acceleration of the engine.

In the event that the engine should abruptly decelerate as the result of the airplane being placed in an extremely high climbing attitude the governor operates in the same manner as it does in connection with abrupt acceleration, except that the inertia member 23, the element 63 and the actuating element 21 moves reversely and the fast rate decrease pitch device 92 is brought into play instead of the fast rate increase pitch device 91. In connection with abrupt deceleration of the engine the governor automatically assumes its no governing or neutral position prior to the engine returning to its predetermined speed. As soon as the governor cuts out or assumes its no governing position the engine, due to the inertia of its parts, levels off or coasts to the predetermined speed and hence hunting of the engine is eliminated in connection with return of the engine to its predetermined speed, i. e., the speed that is governed or controlled by the speed of drive of the pilot motor 19.

By increasing or decreasing the speed of the pilot motor 19 through the medium of the rheostat 56 the engine will be governed so as to run at an increased or decreased predetermined speed. In other words, when it is desired to increase the speed of the engine to any desired R. P. M. the rheostat is adjusted so as to decrease the amount of resistance 56^a in the motor circuit. If it is desired to decrease the speed of the engine the pilot motor is slowed down by manipulation of the rheostat so as to increase the amount of resistance in the motor circuit. By adjusting the rheostat the engine will be controlled automatically by the governor so that it operates at any desired predetermined speed.

The herein described governor is highly efficient in operation and effectively and efficiently fulfills its intended purpose. Its design and construction are such that the tendency of the engine, with which the governor is used, to hunt in connection with governor control is reduced to a minimum. In other words, the governor is so designed and arranged that when the engine acceleration or deceleration ceases under governor control the engine will be operating at the desired or predetermined R. P. M. The governor is characterized by the fact that it is essentially simple in design and hence may be manufactured at a low and reasonable cost. It is essentially in the form of a self-contained unit and is so designed that the parts thereof are not subject to excessive wear.

Whereas the governor has been described as 75

being particularly designed for use in connection with an airplane engine and as controlling the engine through the medium of a controllable pitch propeller it is to be understood that it may be used for other purposes and in other capacities. It is also to be understood that the invention is not to be restricted to the details set forth since these may be modified within the scope of the appended claims without departing from the spirit and scope of the invention.

Having thus described the invention what I claim as new and desire to secure by Letters Patent is:

1. A governor adapted to maintain an engine at a predetermined speed and comprising a rotary member adapted for drive by the engine, a coaxial rotary second member provided with means for driving it at a predetermined speed, a speed control element, means operative automatically when the first mentioned member is driven at a different speed from the second member to actuate the element, and an operating connection between the two members adapted to limit relative rotation of said members and also during drive of said members to urge them to rotate conjointly, and embodying pivot means connected to, and disposed eccentrically of, one of the members, means on the other member forming a concentric arcuate series of teeth, and a rotary element having its central portion supported rotatably by said pivot means and including a concentric arcuate series of teeth in mesh with the first mentioned arcuate series of teeth, stop means at the ends of its arcuate series of teeth, and weight means in opposed relation with its arcuate series of teeth.

2. A governor adapted to maintain an engine at a predetermined speed and comprising a rotary member adapted for drive by the engine, a coaxial rotary second member provided with means for driving it at a predetermined constant speed, a speed control element, means operative automatically when the first mentioned member is driven at a different speed from the second member to actuate the speed control element, and an operating connection between the two members adapted to limit relative rotation of said members and also during drive of said members to urge them to rotate conjointly, and embodying pivot means connected to, and disposed eccentrically of, one of the members, concentric gear teeth on the other member, and a rotary element having its central portion supported rotatably by said pivot means and including an arcuate concentric slot around the gear teeth, an arcuate series of teeth along one side of the slot and in mesh with the gear teeth, and a weight diametrically opposite said arcuate series of teeth.

3. A governor adapted to maintain an engine at a predetermined speed and comprising a rotary member adapted for drive by the engine, a coaxial rotary second member provided with means for driving it at a predetermined constant speed, a speed control element, means operative automatically when the first mentioned member is driven at a different speed from the second member due to acceleration or deceleration of the engine to actuate the speed varying means for engine governing purposes, and an operating connection between the two members adapted to limit relative rotation of said members and also during drive of said members to urge them to rotate conjointly, and embodying a pair of pivots

connected to, and positioned on opposite sides of, one of the members, gear teeth on the other member and a pair of rotary axially offset elements having their central portions supported rotatably by said pivots and each including a concentric arcuate series of teeth in mesh with the gear teeth, stop means at the end of the arcuate series of teeth, and a weight diametrically opposite said arcuate series of teeth.

4. A governor adapted to maintain an engine at a predetermined speed and comprising a slidably mounted speed control element, a shaft adapted for drive by the engine, a coaxial second shaft provided with means for driving it at a predetermined constant speed, an operating connection between the two shafts adapted to limit relative rotation of said shafts and also during drive of said shafts to urge them to rotate conjointly, and embodying pivot means connected to, and disposed eccentrically of, one of the shafts, gear teeth on the other shaft, and a rotary element having its central portion supported rotatably on said pivot means and including a concentric arcuate series of teeth in mesh with the gear teeth, stop means at the ends of the arcuate series of teeth and a weight diametrically opposite said arcuate series of teeth, and means operative when the first mentioned shaft is driven at a different speed from the second shaft due to acceleration or deceleration of the engine from its predetermined speed to slide the element and embodying a collar-like member mounted on, and connected for drive by, said first mentioned shaft and provided with an external screw thread, and a member connected to said second shaft so that it is driven conjointly therewith while at the same time it is permitted to slide relatively thereto, operatively connected to said element and provided with a cam follower type part in engagement with said external screw thread.

5. A governor adapted to maintain an engine at a predetermined speed and comprising, a speed control element, a shaft connected for drive by the engine, a coaxial inertia member rotatably and slidably mounted adjacent the shaft and adapted when slid to actuate the speed control element, a connection between the shaft and the member adapted to cause the member to rotate at the same speed as the shaft when the engine is running at its predetermined speed or gradually accelerates or decelerates from its predetermined speed and also to permit the member to underrun the shaft to a limited extent in connection with abrupt acceleration of the engine and to overrun the shaft to a limited extent in connection with abrupt deceleration of the engine, and including pivot means connected to the member and positioned eccentrically with respect to the shaft, gear teeth on the shaft, and a rotary element having its central portion supported rotatably by said pivot means and embodying a concentric arcuate series of teeth in mesh with the gear teeth, stop means at the ends of the arcuate series of teeth, and weight means in opposed relation with said arcuate series of teeth, and cam type means between the shaft and the inertia member adapted to slide the member in connection with under- or overrunning of the member with respect to the shaft.

6. A governor adapted to maintain an engine at a predetermined speed and comprising, a speed control element, a shaft adapted for drive by the engine, a coaxial inertia member rotatably and slidably mounted adjacent the shaft and adapted when slid to actuate the speed control

element, a connection between the shaft and the member adapted to cause the member to rotate at the same speed as the shaft when the engine is running at its predetermined speed or gradually accelerates or decelerates from its predetermined speed and also to permit the member to underrun the shaft to a limited extent in connection with abrupt acceleration of the engine and to overrun the shaft to a limited extent in connection with abrupt deceleration of the engine, and including a pivot connected to the member and positioned eccentrically with respect to the shaft, gear teeth on the shaft and a rotary element having its central portion supported rotatably by said pivot and embodying a concentric arcuate slot around the gear teeth, a series of teeth along one side of the slot and in mesh with said gear teeth, and a weight diametrically opposite the slot, and cam type means extending between the shaft and the inertia member and adapted to slide the latter in connection with under- or overrunning thereof relatively to the shaft.

7. A governor adapted to maintain an engine at a predetermined speed and comprising, a speed control element, a shaft adapted for drive by the engine, a coaxial inertia member rotatably and slidably mounted adjacent the shaft and adapted when slid to actuate the speed control element, a connection between the shaft and the member adapted to cause the member to rotate at the same speed as the shaft when the engine is running at its predetermined speed or gradually accelerates or decelerates from its predetermined speed and also to permit the member to underrun the shaft to a limited extent in connection with abrupt acceleration of the engine and to overrun the shaft to a limited extent in connection with abrupt deceleration of the engine, and embodying a pair of diametrically opposite pivots on the member, gear teeth on the shaft, and a pair of rotary axially offset elements having their central portions supported rotatably by said pivots and each including a concentric arcuate series of teeth in mesh with the gear teeth, stop means at the ends of the arcuate series of teeth, and a weight diametrically opposite said arcuate series of teeth, and cam type means between the shaft and the inertia member adapted to slide the latter in connection with under- or overrunning thereof with respect to said shaft.

8. A governor adapted to maintain an engine at a predetermined speed and comprising a movably mounted speed control element, a shaft adapted for drive by the engine, a coaxial second shaft provided with means for driving it at a predetermined constant speed, means operative automatically when the first mentioned shaft is driven at a speed different from the second shaft due to gradual variation in the speed of the engine from its predetermined speed to move the control element to a limited extent, an inertia member rotatably and slidably mounted on said first mentioned shaft and operatively connected to the control element so that when it is slid it moves said element to a greater extent, a connection between said first mentioned shaft and the member adapted to cause the member to rotate at the same speed as the first mentioned shaft when the engine is running at its predetermined speed or gradually accelerates or decelerates from its predetermined speed and also to permit the member to underrun the first mentioned shaft to a limited extent in connection with abrupt acceleration of the engine and to overrun said first mentioned shaft to a limited

extent in connection with abrupt deceleration of the engine, and embodying pivot means connected to the member and positioned eccentrically with respect to the first mentioned shaft, gear teeth on said first mentioned shaft, and a rotary element having its central portion supported rotatably by said pivot means and embodying a concentric arcuate series of teeth in mesh with the gear teeth, stop means at the ends of the arcuate series of teeth, and a weight diametrically opposite said arcuate series of teeth, and means between said first mentioned shaft and the inertia member adapted to slide said member in connection with under- or overrunning of the member with respect to said first mentioned shaft.

9. A governor adapted to maintain an engine at a predetermined speed and comprising a slidably mounted speed control element, an engine driven shaft, a coaxial second shaft provided with means for driving it at a predetermined constant speed, means operative automatically when the engine driven shaft is driven at a speed different from the second shaft due to gradual variation in the speed of the engine from its predetermined speed to slide said control element to a limited extent, an inertia member rotatably and slidably mounted on said engine driven shaft and operatively connected to the control element so that when it is slid it slides said element to a greater extent, a connection between the engine driven shaft and the member adapted to cause the member to rotate at the same speed as the engine driven shaft when the engine is running at its predetermined speed or gradually accelerates or decelerates from its predetermined speed and also to permit the member to overrun said engine driven shaft to a limited extent in connection with abrupt acceleration of the engine and to overrun said engine driven shaft to a limited extent in connection with abrupt deceleration of the engine, and embodying a pair of pivots on opposite sides of the member, gear teeth on the engine driven shaft and a pair of rotary axially offset elements having their central portions supported rotatably by said pivots and each including a concentric arcuate series of teeth in mesh with the gear teeth, stop means at the ends of the arcuate series of teeth, and a weight diametrically opposite said arcuate series of teeth, and a screw thread connection between the engine driven shaft and the inertia member adapted to slide the member in connection with under- or overrunning thereof relatively to said engine driven shaft.

10. A governor adapted to maintain an engine at a predetermined speed and comprising a slidably mounted speed control element, a shaft adapted for drive by the engine, a coaxial second shaft provided with means for driving it at a predetermined constant speed, means operative automatically when the first mentioned shaft is driven at a speed different from the second shaft due to gradual variation in the speed of the engine from its predetermined speed to slide said control element to a limited extent, an operating connection between the two shafts adapted to limit relative rotation of said shafts and also during drive of said shafts to urge them to rotate conjointly and embodying pivot means connected to, and disposed eccentrically of, the first mentioned shaft, gear teeth on said second shaft, and a rotary element having its central portion supported rotatably by said pivot means and including a concentric arcuate series of teeth in mesh

5 with the gear teeth, stop means at the ends of the arcuate series of teeth, and a weight diametrically opposite said arcuate series of teeth, an inertia member rotatably and slidably mounted on said first mentioned shaft and operatively connected to the control element so that when it is slid it slides said element to a greater extent, a connection between said first mentioned shaft and the member adapted to cause the member to rotate at the same speed as the first mentioned shaft when the engine is running at its predetermined speed or gradually accelerates or decelerates from its predetermined speed and also to permit the member to overrun the first mentioned shaft to a limited extent in connection with abrupt acceleration of the engine and to overrun said first mentioned shaft to a limited extent in connection with abrupt deceleration of the engine, and embodying an eccentrically disposed pivot on the member, gear teeth on said first mentioned shaft and a rotary element having its central portion supported rotatably by said pivot means and embodying an arcuate series of teeth in mesh with the last mentioned gear teeth, stop means at the ends of the arcuate series of teeth, and a weight diametrically opposite said arcuate series of teeth, and means between said first mentioned shaft and the inertia member adapted to slide said member in connection with under- or overrunning of the member with respect to said first mentioned shaft.

20 11. A governor adapted to maintain an engine at a predetermined speed, and comprising a slidably mounted speed control element, an electric pilot motor, a pair of rotatably mounted coaxial shafts, means for connecting one of the shafts to one of the driven parts of the engine including a hydraulic clutch, a driving connection between the other shaft and the motor, means operative 25 automatically when the engine driven shaft is driven at a different speed from the motor driven shaft due to gradual acceleration or deceleration of the engine to shift the control element to said limited extent, an operating connection between the two shafts adapted to limit relative rotation of said shafts and also during drive of said shafts to urge them to rotate conjointly, and embodying a pair of pivots connected to, and positioned on opposite sides of, the engine driven shaft, gear teeth on the motor driven shaft, and a pair of rotary axially offset elements having their central portions rotatably supported on said pivots and each including a concentric arcuate series of teeth in mesh with the gear teeth, stop means at 30 the ends of the arcuate series of teeth, and a weight diametrically opposite said arcuate series of teeth, an inertia member rotatably and slidably mounted on the engine driven shaft and operatively connected to the control element so that in response to slide thereof it slides the element to a greater extent, a connection between the engine driven shaft and the member adapted to cause the member to rotate at the same speed as the engine driven shaft when the engine is running at its predetermined speed or gradually accelerates or decelerates from its predetermined speed and also to permit the member to overrun the shaft to a limited extent in connection with abrupt acceleration of the engine and to overrun said first mentioned shaft to a limited extent in connection with abrupt deceleration of the engine, and embodying a pair of diametrically opposite pivots on the inertia member, gear teeth on the engine driven shaft, and a pair of rotary axially offset elements having their central portions sup-

ported rotatably on the last mentioned pivots and each including a concentric arcuate series of teeth in mesh with the last mentioned gear teeth, stop means at the ends of the last mentioned arcuate series of teeth, and a weight diametrically opposite said arcuate series of teeth, and a screw thread connection between the engine driven shaft and the inertia member adapted to slide the member in connection with under- or overrunning thereof relatively to said engine driven shaft.

12. A governor adapted for use with a prime mover and comprising a rotary member adapted to be driven by the prime mover, a second rotary member provided with means for driving it at a predetermined speed, a speed control element, means operative upon relative rotation of said rotary members to actuate said element, and an operating connection between the two members arranged and designed to limit relative rotation of said members and operative during drive of

said members and in response to centrifugal action to urge the members to rotate conjointly.
